UNITED STATES PATENT OFFICE

138,602

DESIGN FOR A BOTTLE OR SIMILAR ARTICLE OF MANUFACTURE

Judith McCullough Graydon Merralls, West Los Angeles, Calif., assignor to Carlos E. P. Guerra, Hollywood, Calif.

Application June 8, 1944, Serial No. 113,920

Term of patent 7 years

(Cl. D58—6)

To all whom it may concern:

Be it known that I, Judith McCullough Graydon Merralls, a citizen of the United States, residing at West Los Angeles, in the county of Los Angeles, State of California, have invented a new, original, and ornamental Design for Bottle or Similar Article of Manufacture, of which the following is a specification, reference being had to the accompanying drawing, forming part thereof.

I claim:

The ornamental design for bottle or similar article of manufacture, as shown.

JUDITH McCULLOUGH
GRAYDON MERRALLS.
